UNITED STATES PATENT OFFICE.

DAYTON M. MILLS, OF ARMADA, MICHIGAN.

AIRPLANE.

1,380,576.

Specification of Letters Patent. Patented June 7, 1921.

Application filed March 21, 1919. Serial No. 284,197.

To all whom it may concern:

Be it known that I, DAYTON M. MILLS, citizen of the United States, residing at Armada, county of Macomb, State of Michigan, have invented a certain new and useful Improvement in Airplanes, and declare the following to be a full, clear, and exact description of the same, such as will enable others skilled in the art to which it pertains to make and use the same, reference being had to the accompanying drawings, which form a part of this specification.

My invention relates to airplanes and has for its object to provide an airplane of an improved construction and in this construction a special provision is made for controlling the direction of flight and for retarding the velocity of the plane when it is about to come to land.

20 I secure this object in the device illustrated in the accompanying drawings in which:

Figure 1 is a plan view of an airplane embodying my invention, a part of the upper supporting plane being broken away.

25 Fig. 2 is a side elevation of the same, the body being broken away in part.

Fig. 3 is a detail side elevation partly in section on the line 111—111 Fig. 4.

30 Fig. 4 is a part plan view, to an enlarged scale, showing a portion of the flight-directing aerofoil and adjacent parts of the frame.

Fig. 5 is a detail section on the line V—V Fig. 4.

35 Fig. 6 is a detail plan view of a portion of the steering mechanism.

Fig. 7 (Sheet 1) is a side elevation partly in section showing the pivoted planes and their operating mechanism.

40 *a* is the body of an airplane and *b* is the actuator therefor; *c* indicates the upper sustaining plane or planes and *g* *g*⁵ indicate the lower sustaining planes. These latter are pivoted on horizontal axes extending in 45 a direction transverse to the axis of the plane and are arranged in pairs on each side of the body of the plane.

d is a portion of the flight-controlled aerofoil adapted to be oscillated about an axis 50 coincident or parallel with that of the plane body. *d*³ is an extension of the surfaces *d* *d* there being a pivot *d*⁴ between the portions *d* and *d*³ which permits the latter to turn about a transverse axis at *d*⁴ to serve 55 as an elevator for the plane. *e* *e*² are controlling cables secured to an arm or arms

toward the rear edge of the surface *d*³, said arms extending in opposite directions from said surface at right angles thereto.

f is a lever adapted to be oscillated about 60 a pivot *f*² by the hand of the aviator. This lever has arms extending in opposite directions from its pivotal point *f*². The cable *e*² is secured at one end to an arm at the outer edge of and above the portion *d*³ of 65 the aerofoil *d* *d*³ and at its other end to the lever arm *f* above the pivot *f*². The cable *e*² is similarly secured below the pivots *f*² and *d*⁴.

*h*¹⁰ is a conical gear wheel bearing upon 70 the frame of the airplane with its axis horizontal and approximately parallel to the axis of the body. *h*¹¹ is a conical gear wheel resting in vertical bearings on the frame of the airplane, its teeth engaging with the 75 teeth of the gear wheel *h*¹⁰. *h*¹² is a foot lever by which the gear wheel *h*¹¹ may be oscillated to oscillate the gear wheel *h*¹⁰. *h* *h*² are steel rods extending parallel to each other upon opposite sides of the axis of the 80 wheel *h*¹⁰ and parallel to said axis. The forward ends of the rods *h* *h*² are rigidly secured to the web of the gear wheel *h*¹⁰ and extend through rotatable trunnions *a*⁵ 85 *a*⁵ which rest in bearings on the frame *a*² *a*² of the airplane. *h*³ *h*⁴ are rods secured at one end to the rod *h* extending outward at right angles thereto and having a part of the aerofoil *d* rigidly secured thereto. *h*⁷ 90 and *h*⁸ are rods similar and similarly located to *h*³ and *h*⁴ but upon the opposite side of the frame *a*² and having the corresponding portion of the aerofoil *d* rigidly secured thereto.

*f*³ is a double armed lever extending fore 95 and aft from the pivot *f*² of the lever *f*.

*g*³ is a connecting rod pivoted at one end to the forward edge of the plane *g* and at its other end to the rear end of the arm *f*³. *g*⁴ is a similar connecting rod pivoted at 100 one end to the forwardly extending portion of the lever arm *f*³ and at its other and upper end to the rear edge of the forward plane *g*⁵.

The operation of the above described device is as follows:

By oscillating the lever *h*¹² the aviator may turn the aerofoil *d* about its longitudinal axis, as indicated in dotted lines in Fig. 5, thus presenting a resultant side resistance or lateral resistance to any motion of the plane in that direction. By manipu-

lating the lever f the elevator d^3 may be oscillated about its axis d^4 to control the vertical direction of the airplane.

When the airplane is approaching the earth and is about to land, the planes g g^5 may be turned about their axes g^2 g^6 to tend to elevate the plane and at the same time to interpose an obstacle to the forward motion of the plane.

10 I claim—

1. An aero foil, two parallel pivoted rods adjacent and parallel to the axis of said aero foil and resting in bearings so that each shall be capable of oscillating about its axis, each of said rods being provided with a rigid, laterally-extending arm extending in a direction away from the other of said rods and secured to said aero foil, and means for simultaneously rotating said rods in the 20 same direction.

2. An aero foil, two parallel pivoted rods adjacent and parallel to the axis of said aero foil and resting in bearings so that each shall be capable of oscillating about its axis, each of said rods being provided with a rigid, laterally-extending arm extending in a direction away from the other of said rods and secured to said aero foil, and a part rotatable about an axis in a plane through the 25 axes of said rods and between said axes, said rods being rigidly attached to said part on opposite sides of its center.

3. In an air plane, a pivoted lever having an arm extending forwardly from its axis 30 and an arm extending rearwardly from its axis, a pivoted plane located in front and

above said lever, a second plane located in the rear of and below said lever, a connecting rod extending from the first plane at the rear of its axis to the first-mentioned arm 40 and a connecting rod extending from the second plane in front of its axis to the rearwardly extending arm of said lever.

4. In an air plane, a pivoted lever having an arm extending forwardly from its axis 45 and an arm extending rearwardly from its axis, a pivoted plane located in front and above said lever, a second plane located in the rear of and below said lever, a connecting rod extending from the first plane at the rear of its axis to the first-mentioned arm 50 and a connecting rod extending from the second plane in front of its axis to the rearwardly extending arm of said lever, and means for securing said lever arm at different angular positions.

5. In an air plane, a pivoted lever having an arm extending forwardly from its axis and an arm extending rearwardly from its axis, a pivoted plane located in front and 60 above said lever, a second plane located in the rear of and below said lever, a connecting rod extending from the first plane at the rear of its axis to the first-mentioned arm and a connecting rod extending from the 65 second plane in front of its axis to the rearwardly extending arm of said lever, and an elevator secured to said lever so as to be operated thereby.

In testimony whereof, I sign this specification.

DAYTON M. MILLS.
